UNITED STATES PATENT OFFICE

158,251

HOBBYHORSE

Joseph J. Couzens, Oak Park, Ill., assignor to Sears, Roebuck and Co., Chicago, Ill., a corporation of New York

Application February 15, 1949, Serial No. 866

Term of patent 14 years

(Cl. D34—15)

To all whom it may concern:

Be it known that I, Joseph J. Couzens, a citizen of the United States and a resident of Oak Park, in the county of Cook and State of Illinois, have invented a new, original, and ornamental Design for a Hobbyhorse, of which the following is a specification, reference being had to the accompanying drawing, forming a part thereof.

Fig. 1 is a perspective view of the hobbyhorse, showing my new design; and

Fig. 2 is a perspective view thereof taken from a slightly different angle.

The side not seen in the drawings is substantially the same as the side shown therein.

I claim:

The ornamental design for a hobbyhorse, as shown and described.

JOSEPH J. COUZENS.
